TRASH RECEPTACLE

Eleanor V. Kingsley, P.O. Box 104, Pomona, Calif.

Filed Aug. 3, 1964, Ser. No. 31,121

Term of patent 14 years

(Cl. D58—17)

FIG. 1 is a perspective view of a trash receptacle, showing my new design.

FIG. 2 is a front elevational view thereof.

FIG. 3 is a side view.

FIG. 4 is a top plan view to a smaller scale.

FIG. 5 is a bottom plan view to the scale of FIG. 4.

The side not shown is a mirror image of the side shown and the rear is the same in appearance as the front except for the absence of the hinge element.

I claim:

The ornamental design for a trash receptacle, substantially as shown and described.
